(57) **CLAIM**

The ornamental design for the display device with a keyboard, as shown and described.

DESCRIPTION

FIG. 1 is a front perspective view of the display device with a keyboard in a first folded state according to an embodiment;

FIG. 2 is a front view thereof;

FIG. 3 is a rear view thereof;

FIG. 4 is a left side view thereof, with the right side view being a mirror image;

FIG. 5 is a top view thereof; and

FIG. 6 is a bottom view thereof;

FIG. 7 is a front perspective view of the display device with a keyboard in a second folded state according to the embodiment;

FIG. 8 is a front view thereof;

FIG. 9 is a rear view thereof;

FIG. 10 is a left side view thereof, with the right side view being a mirror image;

FIG. 11 is a top view thereof; and

FIG. 12 is a bottom view thereof;

FIG. 13 is a front perspective view of the display device with a keyboard in an unfolded state according to the embodiment;

FIG. 14 is a front view thereof, with the rear view being a mirror image;

FIG. 15 is a left side view thereof, with the right side view being a mirror image;

FIG. 16 is a top view thereof;

FIG. 17 is a bottom view thereof; and,

FIG. 18 is a rear perspective view thereof.
